(57) **CLAIM**

The ornamental design for a toy hand, as shown and described.

DESCRIPTION

FIG. 1 is a top front perspective view of a toy hand showing our new design, according to a first embodiment;
 FIG. 2 is another top front perspective view thereof;
 FIG. 3 is a top rear perspective view thereof;
 FIG. 4 is another top rear perspective view thereof;
 FIG. 5 is a bottom front perspective thereof;
 FIG. 6 is another bottom front perspective view thereof;
 FIG. 7 is a bottom rear perspective view thereof;
 FIG. 8 is another bottom rear perspective view thereof;
 FIG. 9 a front elevational view thereof;
 FIG. 10 is a right side elevational view thereof;
 FIG. 11 is a rear elevational view thereof;
 FIG. 12 is a left side elevational view thereof;
 FIG. 13 is a top plan view thereof; and,
 FIG. 14 is a bottom plan view thereof.
 The portions illustrated in broken lines form no part of the claimed design.
